CLAIM

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is another a second image thereof; and,

FIG. 3 is another a third image thereof.

The outermost broken lines in the figures show a display screen or portion thereof, and form no part of the claimed design. The other broken lines in the figures show portions of the animated graphical user interface that form no part of the claimed design.

The subject matter in this patent includes a process or period in which an image changes into another image. This process or period forms no part of the claimed design.

1 Claim, 3 Drawing Sheets

FIG. 1

FIG. 2

FIG. 3

UNITED STATES PATENT AND TRADEMARK OFFICE
CERTIFICATE OF CORRECTION

PATENT NO. : D807,906 S
APPLICATION NO. : 29/588013
DATED : January 16, 2018
INVENTOR(S) : Dye et al.

Page 1 of 1

It is certified that error appears in the above-identified patent and that said Letters Patent is hereby corrected as shown below:

On the Title Page

Page 3, Column 1 in the Description, please change Lines 4 and 5 as follows:

“Figure 2 is another a second image thereof; and,
Figure 3 is another a third image thereof.”

Should be:

--Figure 2 is a second image thereof; and
Figure 3 is a third image thereof.--

Signed and Sealed this
Second Day of April, 2019

Andrei Iancu
Director of the United States Patent and Trademark Office
